(57) **CLAIM**

The ornamental design for a ground star light as shown and described.

DESCRIPTION

FIG. 1 is a first perspective view of a ground star light showing my new design;

FIG. 2 is a second perspective view of the ground star light thereof;

FIG. 3 is a front elevational view of the ground star light thereof;

FIG. 4 is a rear elevational view of the ground star light thereof;

FIG. 5 is a left side view of the ground star light thereof; FIG. 6 is a right side view of the ground star light thereof; FIG. 7 is a top plan view of the ground star light thereof; FIG. 8 is a bottom plan view of the ground star light thereof; and,

FIG. 9 is an enlarged view of part 9 in FIG. 1.

The dash-dot broken lines in FIGS. 1 and 9 are for the purpose of illustrating the boundary of the enlarged view and form no part of the claimed design.

The ground star light is shown with a symbolic break in its length in FIGS. 1–6. The break lines and appearance of any portion of the article between the break lines form no part of the claimed design.
